UNITED STATES PATENT OFFICE.

WILLIAM M. DOUGHERTY, OF ST. JOSEPH, MISSOURI.

BALLOTING-MACHINE.

SPECIFICATION forming part of Letters Patent No. 769,537, dated September 6, 1904.

Original application filed June 4, 1902, Serial No. 110,161. Divided and this application filed March 11, 1904. Serial No. 197,633. (No model.)

To all whom it may concern:

Be it known that I, WILLIAM M. DOUGHERTY, a citizen of the United States, and a resident of St. Joseph, in the county of Buchanan and State of Missouri, have invented a new and Improved Ballotting-Machine, of which the following is a full, clear, and exact description.

This application is a division of my application for patent on balloting-machines filed

10 June 4, 1902, Serial No. 110,161.

The present invention relates to certain improved interlocking devices by which a voter is prevented from operating more than one of the counters at the same time.

15 This specification is an exact description of one example of my invention, while the claims define the actual scope thereof.

Reference is to be had to the accompanying drawings, forming a part of this specification, 20 in which similar characters of reference indicate corresponding parts in all the views.

Figure 1 is a plan view of a portion of a balloting-machine having my improvement applied. Fig. 2 is a sectional elevation on the 25 line 2 2 of Fig. 1, and Fig. 3 is a plan view of one of the sections or lock-plates.

12 indicates the arms which operate the counters, one of which counters is indicated in outline in Fig. 1.

30 To prevent two or more of the arms 12 from being drawn down simultaneously, I provide the lock-plates 53. These lock-plates are one for each numbering device or counter and are mounted horizontally, so that all of the lock- 35 plates of one horizontal row are in alinement. The ends of said lock-plates are beveled, as indicated at 53^a, and these beveled ends are reduced and overlapped, as indicated best in Fig. 2. It will be observed that by reducing

40 the ends of the lock-plates shoulders are formed which limit the independent sliding movement of the lock-plates. Suitably-mounted springs 54 are provided for each lock-plate, these springs engaging studs 53^c on the 45 lock-plates yieldingly to hold them in the intermediate position. (Shown in Fig. 2.) 55 indicates pins or screws which are passed through longitudinally-disposed slots 53^b in the lock-plates, and by means of these devices

the lock-plates are mounted to have a limited 50 horizontal movement independently of each other. The beveled ends 53^a of the lock-plates lie immediately under the arms 12, as shown in Fig. 2. When one of the arms is drawn downward, it engages the beveled edges 53^a 55 below it and divides the lock-plates into two divisions, the shoulders (formed by the reduced ends of the lock-plates) engaging in pairs and causing the two divisions of lock-plates to move as units toward the respective 60 ends of the row of numbering devices. This allows the said arm which has been operated to move down wholly unobstructed; but it displaces the lock-plates with respect to the other arms, and as these arms are in a raised position it will be impossible to move them downward so long as the first arm is lowered. If it be attempted to move all of the arms 12 65 down simultaneously, it is clear that there will be no relative movement of the lock-plates 53, 70 and consequently all of the arms will be locked. The springs 54 serve to hold the lock-plates in the position shown in Fig. 2; but they yield to permit the lock-plates to move toward either end, as their operation may require. 75

Various changes in the form, proportions, and minor details of my invention may be resorted to at will without departing from the spirit and scope thereof. Hence I consider myself entitled to all such variations as may 80 lie within the intent of my claims.

Having thus described my invention, I claim as new and desire to secure by Letters Patent—

1. In a balloting-machine, the combination with the swinging arms to register the ballots, 85 of the lock-plates having beveled and reduced contiguous ends lying adjacent to the arms, said contiguous ends of the lock-plates being overlapped at their reduced portions.

2. In a balloting-machine, the combination 90 with the swinging arms which register the ballots, of the lock-plates having beveled contiguous ends lying adjacent to the arms and said lock-plates having limited independent sliding movement, and springs respectively engaged 95 with the lock-plates for holding said lock-plates independently yieldingly in position.

3. In a balloting-machine, the combination

of the swinging arms which register the ballots, lock-plates having beveled contiguous ends lying adjacent to the arms, said lock-plates having limited independent sliding movement, for the purpose specified, and each lock-plate having a stud thereon, and springs supported independently of the lock-plates, said springs having arms lying on opposite sides of the studs and serving to hold the lock-plates yieldingly in central position.

4. In a balloting-machine, the combination with the arms which register the ballots, of the lock-plates having beveled contiguous ends lying adjacent to the arms, the said contiguous ends of the lock-plates being overlapped and having shoulders to limit their independent movement.

5. In a balloting-machine, the combination with the arms which register the ballots, of the lock-plates having beveled contiguous ends lying adjacent to the arms, the said contiguous ends of the lock-plates being overlapped and

the lock-plates having limited, independently-slidable movement, and a spring for each lock-plate, said springs respectively yieldingly holding the lock-plates. ²⁵

6. In a balloting-machine, the combination with the movable arms which register the ballots, of the lock-plates having beveled and reduced contiguous ends lying adjacent to the arms, said contiguous ends of the lock-plates being overlapped at their reduced portions and the lock-plates having independent sliding movement, and a spring for each lock-plate, said springs respectively yieldingly holding the lock-plates. ³⁰

In testimony whereof I have signed my name to this specification in the presence of two subscribing witnesses.

WILLIAM M. DOUGHERTY.
